LAMP GUARD AND SUPPORT

Louis B. Pierce, Klamath Falls, Oreg.

Application July 25, 1939, Serial No. 286,452

10 Claims. (Cl. 240—54)

The present invention relates to a combined lamp handle and guard for extension lights.

It is an object of the invention to provide an improved lamp handle with a readily detachable guard member of improved construction.

Another object of the invention is to provide improved means for retaining a lamp socket in the handle.

Another object of the invention is to provide a lamp handle having means for supporting the same or clamping the same to an object or supporting surface.

Another object of the invention is to provide an improved guard member and improved means for detachably securing the same in position on the handle.

Other objects and advantages of the invention will be apparent from the following detailed description and upon reference to the accompanying drawings, wherein—

Fig. 1 is a plan view of a lamp handle and guard embodying the invention.

Fig. 2 is an axial section parallel to the plane of the sheet of Fig. 1.

Fig. 3 is a fragmentary section on the line 3—3 of Fig. 1.

Fig. 4 is a section on the line 4—4 of Fig. 1.

Fig. 5 is a section on the line 5—5 of Fig. 2.

Fig. 6 is a detail view on an enlarged scale showing the construction of the handle clamping portion of the guard.

Fig. 7 is a section, on a larger scale, on the line 7—7 of Fig. 6.

Fig. 8 is a fragmentary section through the end of the casing, on the line 8—8 of Fig. 1, and

Fig. 9 is a section on the line 9—9 of Fig. 8.

Referring more particularly to the drawings, 10 indicates a tubular handle formed with a bore 11 and an enlarged head 12 at one end. The bore 11 is enlarged in the head 12 to provide a chamber 13 for the reception of a weatherproof rubber lamp socket 14. The outside of the socket 14 is provided with circumferentially spaced lugs 15 spaced from the end thereof, and the wall of the 45 chamber 13 is provided with correspondingly spaced longitudinal channels 16 for the reception of the lugs 15 when the socket 14 is inserted into the chamber 13. The socket is also provided with an annular end flange 17 which seats on the 50 shoulder 18 of the head 12 when the socket is in position.

The socket 14 is held in place in the chamber 13 by an expanding spring ring 19 which seats in a groove 20 in the head 12 adjacent the outer 55 end of the chamber 13, the spring ring having

one end projecting out in the nature of a finger piece 19a so that the ring can readily be removed by hand. The lugs 15 engaging the channels 16 prevent rotary motion of the lamp socket in the handle and the spring ring 19, confining the annular flange 17 against the shoulder 18, prevents axial movement thereof.

The lamp guard 21, according to the invention, is made up of a plurality of resilient spring wires 22 which are rigidly secured together at a common junction point by welding or otherwise, as indicated at 23. The wires 22 loop inwardly from the junction point 23 and are equally spaced from each other, producing a cage for the lamp bulb.

The inwardly directed ends of the guard wires 22 are each secured as by welding to a round arcuate metal section 24. The sections 24 are dimensioned so that when the guard wires are in contracted relation, the sections 24 abut endwise to form a ring fitting within a circumferential groove 25 adjacent the outer end of the head 12. The guard wires are spring tensioned so that the ends normally tend to spring together and thus contract the ring formed by the segments 24 into tight gripping engagement with the groove 25.

The end of the head portion 12 of the handle casing is tapered from both the inner annular groove 20 and the outer circumferential groove 25 to its extremity, as indicated at 26 and 27, 30 respectively, to facilitate mounting of the spring ring 19 and guard 21. Due to the tapered end formation, these members may readily be shoved into position, the tapered surfaces guiding them to the respective seats.

In order to insure firmer engagement of the guard 21 on the handle, a contractile coil spring 28 is provided, surrounding the split ring produced by the segments 24. The spring 28 is assembled with the guard parts by screwing the same onto the segments 24 while they are in contracted relation, this being necessitated because the coils of the spring must pass the guard wires 22 connected to the segments. The ends of the spring 28 after assembly are hooked together or 40 are secured to one end of one of the guard wires so that it is in effect an endless coil. The contractile spring instead of surrounding the segments 24 could be threaded through the latter since they are in tubular form.

In order to eliminate any frictional drag between the segments 24 and the spring 28, the segments are preferably tapered toward the ends on the outer surfaces thereof as indicated at 29 in Fig. 6. This construction, permitting free mo- 55

tion of the segments in the coil spring without frictional drag results in firmer clamping of the guard on the handle and thus increases the rigidity of the assembly.

5 The guard member 21 is provided with a folding supporting hook 30 and a reflector and light shield 31. The hook 30 is swiveled on one of the guard wires adjacent the junction 23 by having one end turned around the same as at 32 and is 10 shaped so as to conform to the shape of the cage when folded to the position shown in Fig. 1. The reflector and light shield 31 is secured to the same guard wire section as is the hook 30, the upper edge of the reflector serving to maintain the swiveled end 32 of the hook in position adjacent the junction 23 of the wires. The hook 30 being formed of resilient wire may have the free end thereof sprung under one of the guard wires to hold it fast in collapsed position when not in use. 15 The reflector plate 31 is curved to conform to the normal contour of the guard cage and may be welded or otherwise secured to the guard wire on which it is mounted.

20 The cord end of the handle 10 is formed with an axial bore 33 to pass the extension cord 34 and is recessed at opposite sides for a purpose to be presently described. The recessing of the end of the casing produces a central section 35 of reduced thickness between the recesses, and the 25 walls of this section 35 are in turn recessed on opposite sides as at 36. The recesses 36 extend across the cord channel 33 and a pair of cord clamping plates 37 disposed in the recesses 36 are brought into clamping engagement with the cord 34 by clamping bolts 38 extending through the 30 wall of the projecting end of the handle. Thus, any strain on the cord 34 is taken up by the clamp and is not transmitted to the socket connection.

40 The wire terminals 40 of the cord 34 are connected to the socket wires 41 by means of solderless connectors of the threaded socket type.

45 In order to provide for mounting the lamp handle on a suitable flat support, or clamping the same in position on a supporting member such as a shelf, post or the like, a folding stand or clamp is mounted on the handle 10. This stand comprises a pair of pivotally connected arms 43, shaped to lie flat against the casing seated in 50 channels formed in the surface of the same when in collapsed position, as shown. The arms 43 are pivoted together at their forward ends as at 44 and one of them is formed with a socket extension 45 which constitutes a ball socket 46 of a ball and 55 socket joint. The ball part 47 of the joint is carried by a plate 48 riveted to the handle 10 and disposed in a recess 49 in the handle at the junction of the head 12 therewith.

60 The bracket arms 43 each have a foot pad 50 pivotally connected to the rear ends thereof, the pads 50 being disposed in the recesses 51 formed at the end of the handle 10 as previously mentioned. The pads 50 are shaped to conform to the contour of the handle when disposed in the 65 recesses 51.

70 Provision is made for grounding the guard cage and supporting bracket through the medium of a metal strip 52, one end of which extends into the groove 25, as seen in Fig. 3, the strip extending inside the handle casing and being connected to the ball member of the ball and socket joint through the medium of the rivets 53 by which the ball is secured to the casing. A ground wire 54 is connected to the inner end of the strip 52.

75 With this assembly the light may readily be

mounted in any convenient place or attached to a convenient support and the light shield and reflector can be turned to correct position merely by turning the guard around in the groove 25.

80 The guard cage can easily be removed and replaced without use of tools of any kind due to the expansibility of the groove engaging portion thereof, thereby making the replacement of the lamp bulb a simple and convenient operation.

85 While preferred embodiments of the invention have been shown and described by way of illustration, it will be understood that various modifications in the details of construction may suggest themselves and are to be considered as forming part of the present invention, within the scope 10 of the appended claims.

I claim:

1. A lamp guard comprising a handle having a socket mounted in one end thereof, said handle having a circumferential groove adjacent the 20 socket end, a lamp guard comprising a plurality of longitudinally looped resilient members joined at one end at a common center and having the other ends thereof spring tensioned toward a common center, an arcuate cross member secured to the last mentioned end of each of said resilient members, and a contractile coil spring carried by and housing the arcuate cross members thereby forming a resilient collar adapted to engage in said circumferential groove to mount said guard on said handle.

2. A lamp guard comprising a handle having a socket mounted in one end thereof, said handle having a circumferential groove adjacent the 35 socket end, a lamp guard comprising a plurality of longitudinally looped resilient members joined at one end at a common center and having the other ends thereof spring tensioned toward a common center, an arcuate cross member secured to the last mentioned end of each of said resilient members, a contractile coil spring member carried by said arcuate cross members with the latter disposed within said coil to form a resilient collar adapted to engage in said circumferential groove to mount said guard on said handle, 40 and a grounded metal strip having one end extending into said circumferential groove adapted to make contact with a part of said guard when the latter is mounted on said handle.

3. A lamp handle and guard comprising a 50 handle including a rigid body having a socket chamber in one end thereof, the wall of said socket chamber having spaced longitudinal grooves therein, a socket in said chamber having circumferentially spaced lugs adapted to fit in said grooves, a flange adjacent the outer end of said socket, a shoulder adjacent the outer end of said chamber to seat said flange for limiting inward movement of said socket, said handle having an annular groove adjacent said shoulder, a spring ring engaged in said groove and in contact with the flange on said socket to retain said socket in said chamber, said handle having a circumferential groove adjacent the socket end thereof, a guard member comprising a plurality of resilient longitudinal members having inwardly directed ends tensioned toward a common center, arcuate cross members secured to the inner ends of said longitudinal members and a contractile coil spring member carried by said resilient longitudinal members with said arcuate cross members disposed within said coil to form a resilient collar adapted to engage in said circumferential groove to mount said guard on said handle.

4. A lamp guard comprising a handle having a socket mounted in one end thereof, said handle having a circumferential groove adjacent the socket end, a lamp guard comprising a plurality of longitudinally looped resilient members joined at one end at a common center and having the other ends thereof spring tensioned toward a common center, an arcuate cross member secured to the last mentioned end of each of said resilient members and adapted each to engage in said circumferential groove to mount said guard on said handle, a supporting unit swivelled on said handle comprising a pair of pivotally connected arms shaped to conform to the contour of the handle 15 when in a collapsed position, said handle having oppositely disposed recesses adjacent the end thereof opposite said socket, and a foot pad pivotally connected to the free end of each of said arms and adapted to seat in said recesses 20 when said arms are collapsed against the handle.
5. A lamp guard comprising a handle having a socket mounted in one end thereof, said handle having a circumferential groove adjacent the socket end, a lamp guard comprising a plurality of longitudinally looped resilient members joined at one end at a common center and having the other ends thereof spring tensioned toward a common center, an arcuate cross member secured to the last mentioned end of each of said resilient members and adapted each to engage in said circumferential groove to mount said guard on said handle, a ball member mounted on said handle, a supporting unit swivelled on said ball member comprising a pair of pivotally connected arms shaped to conform to the contour of said handle when in a collapsed position, and a grounded metal strip having one end extending into said circumferential groove to contact said guard and extending inside said handle and connected to said ball member to ground the supporting unit carried thereby. 30
6. A combined lamp guard and support comprising a tubular handle member having an enlarged head at one end, a lamp socket mounted in said head, said head having a circumferential groove adjacent the end thereof, a lamp guard comprising a plurality of longitudinally extending resilient members joined together at one end thereof and having the other ends thereof spring tensioned toward a common center, an arcuate cross piece secured to the last mentioned end of each of said resilient members and adapted each to engage in said groove to mount said guard on said head, said handle having oppositely disposed recesses formed in the other end thereof defining a longitudinally extending rib member, said rib 35
- member being axially bored for passage of an electric cable cord and having recesses in opposite sides thereof exposing a cord extending through said bore, cord clamping plates disposed in the recesses in said rib, a supporting unit swivelled on said handle comprising a pair of pivotally connected arms shaped to conform to the contour of said casing when in a collapsed position, and a foot pad pivotally connected to the outer end of each of said arms adapted to seat in said oppositely disposed recesses in the last mentioned end of said handle member when said arms are in collapsed position to conceal said cord clamping plates. 5
7. A lamp holder and guard comprising a handle having a socket mounted in one end thereof, said handle having a circumferential groove adjacent the socket end thereof, a quick detachable guard unit comprising a plurality of longitudinally bowed members joined at one end thereof, an arcuate cross member secured to the other end of each of said bowed members, and a contractile coil spring member carried by said bowed members with said arcuate cross members disposed in the bore of the coil spring to form a resilient collar adapted to seat in said circumferential groove aforesaid. 10
8. A lamp holder and guard according to claim 7 in which said handle is tapered from said circumferential groove to the end thereof to provide a guiding cam surface adapted to expand said resilient collar in mounting the guard unit on the handle. 20
9. A lamp holder and guard comprising a handle having a socket mounted in one end thereof, said handle having a circumferential groove adjacent the socket end thereof, a quick detachable guard unit comprising a plurality of longitudinally bowed members joined at one end thereof, an arcuate cross member secured to the other end of each of said bowed members, said arcuate cross members being substantially circular in cross section and tapered at the ends thereof, and a contractile coil spring member carried by said bowed members with said arcuate cross members disposed in the bore of the coil spring to form a resilient collar adapted to seat in said circumferential groove aforesaid. 25
10. A lamp holder and guard according to claim 9 in which said handle is tapered from said circumferential groove to the end thereof to provide a guiding cam surface adapted to expand said resilient collar in mounting the guard unit on the handle. 30
